(No Model.)

E. A. OLMSSTEAD.

VEHICLE HEATER.

No. 367,997.

Patented Aug. 9, 1887.

UNITED STATES PATENT OFFICE.

EDWARD A. OLMSTEAD, OF NEW YORK, N. Y.

VEHICLE-HEATER.

SPECIFICATION forming part of Letters Patent No. 367,997, dated August 9, 1887.

Application filed October 8, 1886. Serial No. 215,725. (No model.)

To all whom it may concern:

Be it known that I, EDWARD A. OLMSTEAD, of the city, county, and State of New York, have invented a new and Improved Vehicle-
5 Heater, of which the following is a full, clear, and exact description.

This invention relates to vehicle-heaters, the object of the invention being to provide a compact, cheap, and durable heater that is
10 more especially applicable for use as a tram-way or street-car heater, but which may be used in connection with other forms of vehicles.

Reference is to be had to the accompanying
15 drawings, forming a part of this specification, in which similar figures of reference indicate corresponding parts in both the views.

Figure 1 is a central longitudinal sectional view of my improved form of vehicle-heater;
20 and Fig. 2 is an end view of the same, the left-hand portion of the heater being shown in vertical section.

In constructing the heater forming the subject-matter of this application I provide a
25 main boiler, 10, to which there is connected a secondary boiler or drum, 11, said connection being established by means of tubes 13, that are preferably arranged as best shown in Fig. 1. The boiler 10 is mounted within a casing or
30 jacket, 15, to which jacket there is secured a fire chamber or box, 16, the bottom of the forward portion of said box 16 being provided with upwardly-extending and longitudinally-apertured ridges 17.

35 Below the fire-chamber 16 I arrange a lamp-box, 20, said box being formed with an inclined bottom, 19, the front wall of the jacket 16 constituting a portion of the front wall of the lamp-box, as shown at 21. Across the upper
40 portion of the lamp-box I place a perforated metal diaphragm, 22, that is formed with longitudinal slots 23, which slots are so arranged as to permit of the passage of the wick-tubes of the lamps employed in connection with the
45 boilers.

It will be noticed that the bottom of the lamp-box does not extend to the front wall of said box, and in order that the space which would otherwise exist between the front edge
50 of said bottom and the front wall of the box may be closed, I hinge a door or trap, 30, just

in front of the said bottom 19, as clearly shown in the drawings. This door or trap consists of an upwardly and forwardly extending portion, 2, and a vertical portion, 3, a horizontal 55 ledge, 4, being formed, as indicated in Fig. 1. The upper edge of the door is slotted, as shown at 5, and this slot receives a turn-button, 6, carried by the wall 21, the parts being so arranged that when the button is turned to the 60 position shown upon the right in Fig. 2 the door or trap will be held in its closed position. The lamp or fount, which is shown at 40, is of ordinary construction—that is, provided with wick-tubes 41, and wick-raising spindles 65 42, said spindles being in turn provided with thumb-wheels 43. In inserting the fount or founts (for it will be understood that each wick-tube might be arranged in connection with a distinct fount) the door or trap 30 is opened—70 that is, swung to the position indicated by dotted lines in Fig. 1—after which the founts may be inserted within the lamp-box, the incline of the bottom of said box providing for the passage of the wick-tubes within the box. 75 After the founts have been inserted and pushed back to place the door is raised, and as the extending end of the fount is struck by the curved portion of the door 30 said end of the fount will be raised, so that when the door is 80 fully closed the fount will be in a horizontal position, the outer edge of the fount resting upon the ledge 4 of the door 30. The wall 21 is formed with slots 6, through which the spindles 42 pass, similar slots or recesses being 85 formed in the upper edge of the door.

If deemed advisable, the sight-holes that are covered by plates of glass, as 44, may be formed in the sides of the fire-chamber, and the draft of the lamp may be regulated by slides 90 45, arranged to be adjusted so as to regulate the amount of air that is admitted through the apertures 46 of the lamp-box 20. When the lamps are in position for use, they will occupy the position in which they are shown in the 95 drawings—that is, their wick-tubes 41 will pass upward through the slots 23 of the diaphragm 22, the upper ends of the wick-tubes entering the recesses formed by the ridges 17. As the water within the boiler is heated a current will be established and the heated water or steam (should the water become slightly 100

evaporated or diminished in quantity) would pass from the auxiliary boiler by way of a tube, 50, and thence by circulating tubes that are properly arranged about the vehicle to the return-tube 51, by which arrangement I provide for a continuous circulation of the hot water or steam and a reheating of the same after it returns to the boiler. Although I prefer that the main and the auxiliary boilers should be kept filled with water, it will be understood that the device would operate if the water should be materially diminished in quantity. A safety-valve, 60, is provided to prevent any undue pressure upon the boiler, and a filling tube or nozzle that is closed by a cap is arranged in connection with the auxiliary boiler 11, this arrangement being shown at 70. The heat generated by the lamps passes upward and about the boiler, as indicated by the arrows shown in Fig. 2, the waste products of combustion being carried off through a smoke-stack, 80.

In arranging the heater in connection with a tramway or street-car the parts are relatively adjusted, as indicated in Fig. 2, wherein 100 represents the flooring of the car.

Having thus described my invention, what I claim as new, and desire to secure by Letters Patent, is—

1. In a vehicle-heater, the combination, with the lamp-box provided with the inclined bottom, of the curved door hinged to the forward end of said bottom, substantially as and for the purpose specified.

2. In a vehicle-heater, the combination, with the lamp-box provided with the inclined bottom, of the door hinged to the forward end of said bottom, and having a curved portion, 2, a ledge, 4, and a vertical flange, 3, substantially as and for the purpose set forth.

3. In a vehicle-heater, the combination of the following elements, viz: lamp-box 20, having inclined bottom 19, a door, 30, a diaphragm, 22, slotted as described, and a combustion-chamber, the bottom of which is provided with longitudinally-slotted ridges 17, substantially as described.

4. In a vehicle-heater, the lamp-box provided with the slotted diaphragm and the inclined bottom, the curved door hinged to the forward end of said bottom, and a combustion-chamber, the bottom of which is provided with longitudinally-slotted ridges, substantially as and for the purpose set forth.

EDWARD A. OLMSTEAD.
